UNITED STATES PATENT OFFICE.

JOHN S. COREY, OF SAN PEDRO, CALIFORNIA.

VANITY CASE.

Application filed October 27, 1925. Serial No. 65,126.

My invention is a vanity case or box, adapted to carry cosmetics and various other articles and materials for personal adornment.

5 An object of my invention is the construction of a vanity case which may have compartments for loose powder or compacts, a place for one or more powder puffs, separated from the compacts and also having a 10 place or receptacle for a lip stick holder and a perfume bottle.

A further object is to provide a holder contained in the case but maintained distinct therefrom so as to be free of any loose powder or the like, this holder being useful for 15 the carrying of coins.

My vanity case is preferably constructed circular in form and has a mirror mounted in the lid with a spring clip adapted to 20 hold a powder puff, handkerchief or the like. The diaphragm pivotally mounted in the middle portion of the case contains a plurality of compact holders, these holders have hinged lids and being removable so 25 that they may be replaced by other compact holders.

A further feature of the case is a receptacle adjacent the bottom adapted to contain a lip stick holder and a perfume bottle 30 and forming compartments for a plurality of small powder puffs or the like.

A further feature of my invention is the provision of a sliding tray in the base of the holder, the tray being retracted by spring 35 action and opened by engaging the back of the tray through an opening in the base of the holder, the tray therefore being readily opened a sufficient distance to remove coins or the like and automatically retracting when 40 the coins are withdrawn.

My invention and the various features thereof will be more readily understood from the following description and drawings, in which—

45 Figure 1 is a perspective view of my vanity case, looking at the inside of the case, showing the compartment in the base for a lip stick holder and perfume bottle and powder puffs, the sliding tray in the base, 50 the hinged diaphragm having the removable compact holders therein and the lid with a mirror and hook secured to the lid.

Fig. 2 is a longitudinal vertical section through the case in its closed position as 55 if taken on the line 2—2 of Fig. 1, with the diaphragm and lid closed down.

Fig. 3 is a vertical cross section on the line 3—3 of Fig. 2.

Fig. 4 is a section of the hinged diaphragm with the removable compact holders therein, showing the support for a removable holder. 60

Fig. 5 is a plan view of the slidable tray removed from the case.

Fig. 6 is a side elevation of the lip stick holder. 65

Fig. 7 is a longitudinal section of the lip stick holder, indicating a slidable support for the lip stick.

Fig. 8 is an end view of Figs. 6 or 7 in the direction of the arrow 8. 70

The general features of my vanity case are shown particularly in Figs. 1, 2 and 3, in which the base section of the case is designated by the numeral 1, having a lid 2 pivotally mounted on the base by a hinge 3 and held in closed relation by a nub 4 on the lid and a corresponding socket 5 on the base, the lower edge of the rim engaging a beading 6 on the base. 75

The lid has a metal strip 7 around its edge, with a rim 8 engaging the mirror 9 and holding the same in firm position. A spring hook or clamp 10 is secured to a widened section 11 of the strip 7, preferably by means of prongs 12 extending through the strip and clinched on the opposite side. This hook 10 is designed to press tightly against the widened section 11 and to be formed of resilient metal in order to clamp articles firmly in position in the lid. 80

The manner of mounting the compact holders is substantially as follows:

A ledge 13 having an upturned flange 14 is positioned inside the base adjacent the upper edge and may be permanently secured to the base or entirely removable. I prefer a construction in which this ledge is removable but forms a tight fit with the base. A diaphragm 15 is connected by a hinge 16 to the ledge, the hinge preferably being secured to the back portion of the flange 14. A frog 17 is secured to the front edge of the diaphragm and forms a finger grip to hinge the said diaphragm upwardly. The frog is preferably secured to the diaphragm by a pair of prongs 18 extending through apertures in the diaphragm, the prongs being clinched at the lower edge and by a pair of prongs 19 extending downwardly through to the apertures in the diaphragm and forming a guide for the diaphragm as herein-after described. 95

The compact holders 20 are secured in openings 21 in the diaphragm, having partially downwardly pressed sections 22 with inwardly extending rims 23. Each of the compact holders comprises a base 24 and a lid section 25 secured to a hinge 26. The lid and the base are locked together by a nub and socket arrangement or other suitable fastening. These holders are designed to contain cosmetics in a compact form, but may if desired be used for powdered cosmetics. They are readily removable and replaceable by other compact holders containing different kinds of powder or hard rouges.

The base of the vanity box has a false bottom 27 with a longitudinal circular bead 28 forming a narrow slot 29 at the lower portion of the bead. The bottom has downwardly extending sides 30 and is opened at the front and back. The flanges 31 are adapted to form a tight fit against the inside of the base and extend only partially along the bottom 32 of the base, leaving a free space 33 for a lipstick holder and perfume bottle as hereafter described. If desired, the false bottom may be permanently secured to the base by soldering or the like, however, I prefer to have it formed with a tight fit so that the false bottom may be removed if desired.

A tray 34 has a covered section 35 at the inner end with an upwardly extending stud 36 secured to said covered section, this stud being adapted to engage one end of a compression spring 37, the spring being positioned inside the bead 28 of the false bottom and bearing at its other end against the front portion of the base of the vanity case.

The bottom 32 of the base has a cut out section 38 extending from the back of the case about one half way and the rear wall of the base has a cut out section 39. This forms an opening for the fingers to engage the back of the tray and shove the tray outwardly by pressing the spring 37. This tray may be used for holding coins and after extracting a coin closes to the position shown in Fig. 2.

The manner of utilizing my vanity case above described, it is believed will be apparent, however, it may be stated that the lid is secured by a type of fastener which will always maintain it closed and on being opened up exposes the mirror and the hook 10 mounted in the lid. The compact holders removably mounted in the diaphragm are then in convenient position for access, being preferably horizontal as the base of the box is held horizontal in the hand. I have illustrated two compact holders but one may be used or more than two if desired. The lids of these may be readily opened for access to the compacts and the whole dia-

phragm containing the compacts may be hinged upwardly, exposing for use the powder puffs contained in the false bottom and the lip stick holder and perfume bottle.

The prongs 19 engage on opposite sides of the bead 28 and form a guiding device for assuring proper fit of the diaphragm in opening and closing the same. The tray 34 may be readily projected as shown in Fig. 1, by pressing the inner end through the openings 38 and 39 in the base.

In addition to the vanity box I have developed a simple form of lip stick holder shown in Figs. 6, 7 and 8, the holder being made of a strip of metal bent into the form of a cylinder 40 with a slot 41 adjacent the meeting edges and with an outwardly turned edge 42. The strip of metal has two semi-circular shaped pieces 43 and 44 at the base, these being bent over with a center section 45 engaging inside the section 44 and with two outer sections 46 engaging on the inside of the section 43. The bent end 47 of the turned edge 42 presses against the joining edge of the sections 43 and 44 and holds them in position. This forms a rigid type of cylinder without any soldering.

A small slidable holder 48 has a tongue 49 extending outwardly and guided by the turning edge 42, whereby the lip stick may be spread lengthwise of the lip stick holder. The cap 50 is provided with a slot 51 to engage over the edge 42.

This type of lip stick holder is of simple construction forming a device that may be constructed without the use of solder by simply cutting the sheet metal to proper shape and bending the various elements in the desired relation.

The lip stick holder is indicated positioned in the false bottom by the numeral 60 and the perfume bottle by the numeral 61, this latter being of any suitable construction, preferably a metal box suitable to hold a bottle. The portions of the false bottom designated 62 and 63 form a convenient place to hold small powder puffs or beads.

Although I have illustrated my vanity case as for hand use, nevertheless I provide small eyelets 64 to which a chain may be connected or attached. These eyelets are preferably made by utilizing a plate 65 with a series of prongs extending through the wall of the base and having a bent up meeting portion 66 with a ring 67 secured therein.

It will be seen from the above description and illustration that my vanity case is of simple construction and may be utilized for a variety of purposes, holding cosmetics and the like and provides a slidable tray which may be utilized for different purposes. The structure may be considerably changed in shape and its general features to suit differ-

ent forms of ornamentation and sizes and may be otherwise altered without departing from the spirit of my invention as set forth in the description, drawings and claims.

5 Having described my invention, what I claim is:

1. A vanity case comprising a box-like structure formed of a base with a lid hinged thereto, a diaphragm hingedly connected to the base having compact holders mounted therein, a false bottom below the diaphragm and a slidable tray in the false bottom.

10 2. A vanity case as claimed in claim 1, in which the false bottom is spaced from the side walls of the base forming compartments for a lip stick holder and perfume bottle.

15 3. A vanity case as claimed in claim 1, in which the false bottom forms a housing for a spring and the slidable tray is provided with an abutment engaging the spring, said spring being normally tensioned to retain the tray within the false bottom.

20 4. A vanity case as claimed in claim 1, having a spring operatively engaging the base and the tray, adapted to normally retain the tray housed within the base, the bottom of the base having an elongated opening adapted to allow a finger to engage the tray to thrust the tray outwardly.

25 5. In a vanity case, a box-like structure having a base compartment, a tray slidably mounted in said compartment, a spring operatively engaging the base and the tray, adapted to maintain the tray housed, the bottom of the base having an elongated cut out section, said section allowing insertion of a finger to engage and thrust the tray outwardly.

30 6. In a vanity case as claimed in claim 5, having in addition the rear wall of the base formed with a cut out section to allow the insertion of a finger to press against the inner end of the tray.

35 7. In a vanity case as claimed in claim 5,

having in addition a false bottom positioned over the tray, the false bottom having a longitudinal bead adapted to house the spring and the tray having a stud extending upwardly into the said bead and engaging the spring.

40 8. In a vanity case, a box-like structure having a base and a lid, a ledge positioned in the base, a diaphragm hinged to the ledge and compact holders mounted in the diaphragm.

45 9. In a vanity case as claimed in claim 8, in which the diaphragm is provided with openings having downwardly pressed sections with inwardly extending rims and the compact holders are removably positioned, having hinged lids.

50 10. A vanity case comprising in combination a substantially circular box-like structure forming a base, a lid hinged thereto, a diaphragm hingedly mounted in the base, compact holders in said diaphragm, a false bottom in the base, forming a compartment at each side thereof, a tray housed in the base below the false bottom, the base having an opening in the front to allow projection of the tray and having a cut out section in the bottom wall and the rear wall to allow a person's finger to engage the inner end of the tray and a spring mounted in the false bottom operatively engaging the base and the tray, adapted to retain the tray normally in its housed position.

55 11. A vanity case as claimed in claim 10, having in addition a beading formed in the top of the false bottom, forming a housing for the spring and a frog attached to the diaphragm forming a finger grip to lift the diaphragm, said frog having prongs extending downwardly and straddling the bead to form guiding elements.

60 In testimony whereof I have signed my name to this specification.

J. S. CORRY.
